C. E. WICKE

COVER PLATE FOR DISPLAY CASES

Original Filed May 15, 1924

FIG. 1.

FIG. 2.

INVENTOR
CHARLES E. WICKE

BY
Greenbowe & Regis
ATTORNEYS

UNITED STATES PATENT OFFICE.

CHARLES E. WICKE, OF MOUNT VERNON, NEW YORK, ASSIGNOR TO A. C. WICKE MANUFACTURING COMPANY, OF NEW YORK, N. Y., A CORPORATION OF NEW YORK.

COVER PLATE FOR DISPLAY CASES.

Original application filed May 15, 1924, Serial No. 713,393. Divided and this application filed April 6, 1925. Serial No. 21,157.

To all whom it may concern:

Be it known that I, CHARLES E. WICKE, a citizen of the United States, and a resident of 258 East 4th Street, Mount Vernon,

5 Westchester County, and State of New York, have invented a new and useful Improvement in Cover Plates for Display Cases, of which the following is a specification.

The present application is a division of 10 my copending application Serial Number 713,393, filed May 15, 1924, for display cases.

This invention relates to cover plates for display cases and more particularly to a 15 cover plate which is designed to serve as a protector for the woodwork and as a support for the trays and the sliding doors.

An object of my invention is to provide 20 a more sanitary and durable cover plate for display cases.

Another object of my invention is to provide a seamless cover plate which combines trackage facilities for the sliding doors of display cases.

25 A further object of my invention is to improve the track portion of a display case so that such portion constitutes a cover plate to prevent the wooden base portion of the case from deteriorating and which 30 also serves as a support for one end of the removable trays employed in such cases.

A more specific object of my invention is to provide a protection cover plate for a display case which functions to furnish

35 trackage for the sliding doors and to prevent their displacement and also to support one end of the removable trays utilized therein.

Other objects of my invention will be apparent as the description proceeds.

40 Show cases as generally employed for the display of meats and other perishable products are so constructed that the articles may readily be exhibited, this being accomplished by making the enclosing walls about the articles of glass. Access is had 45 to the inside of the case by means of sliding doors which are movable on tracks secured to the lower wooden base structure of the case. Since a show case of the above 50 type is located in a store where the surrounding atmosphere is more or less heated, it is necessary to provide the case with an ice compartment or other cooling means.

55 A prerequisite of show cases in which food products are kept is sanitation, and

it has been found undesirable to expose any of the wooden structure of the case to the moisture which by reason of condensation accumulates within the case.

Considerable complaint and disadvantage 60 has been experienced heretofore by reason of the constant deposits of moisture upon the wooden portions of the case structure between and around the tracks upon which the doors of the case slide. It has been found 65 that this exposed portion of woodwork became foul owing to the fine particles of food, such as meat or vegetables, accumulating thereon, which resulted in the woodwork 70 rotting and emanating offensive odors; thus defeating one of the important purposes for which such show cases were primarily designed.

The present invention aims to prevent the 75 above disadvantages by providing a cover plate for the heretofore exposed woodwork and combines with the cover plate one or more tracks upon which the doors may ride. In addition to the combination of the cover plate and tracks, the invention also provides 80 a ledge or support which serves as one portion of a tray rest. The cover plate is so designed as to also furnish a stop so as to prevent movement of the doors from their position on the tracks.

85 The present invention, therefore, not only promotes the sanitary conditions of the display case but serves mechanically as a smooth-running track for the doors.

The cover plate and track is, in accordance with my invention, so constructed that it may be produced in the form of a continuous strip of any desirable length as an article of manufacture and the strips may thus be sold in commerce to be cut to size 90 on the job where the strip is to be used.

When the present invention is incorporated in a show case the appearance of the structure is not only enhanced, but greater 95 rigidity and general structural strength is added as well as the elimination of many corners and crevices which have heretofore served to collect dirt and moisture which give rise to obnoxious odors. For the purposes of further enhancing the usefulness 100 of my strip or plate, I may make the same of a material impervious to moisture and non-corrosive, as for example, of Monel metal and the like.

105 The invention will be better understood 110

by referring to the accompanying drawing, in which

Fig. 1 is a fragmentary perspective view of a portion of a cover plate embodying my invention, and

Fig. 2 is sectional view of a portion of a show case showing the present invention on an enlarged scale, and also showing, in dotted lines, the operative relation thereto 10 of sliding doors.

In the drawing the present invention is shown as manufactured for use in connection with display cases and is also shown in place to cover an edge of a wall of a compartment to protect the same and to provide guides for sliding doors.

The selected embodiment of the present invention may comprise a strip 2 suitably shaped to serve as a cover for an edge 3 of a wall 4 of the supporting structure of a show case.

The strip 2 may be of sheet metal shaped to provide one or more rails or tracks 6 to slidably support doors 7 and 8 shown in 25 dotted lines in Fig. 2. The doors may be provided with grooved edges to receive the tracks or when desirable may be provided with rollers in the usual manner to traverse the tracks 6.

30 The doors 7 and 8 when constantly used, as is the case when the display case is in a store, are subjected to considerable misdirected force to effect their edgewise movement, which force results in a side thrust 35 tending to derail the doors. The present invention, however, provides a ridge or stop 9 so positioned as to be in close proximity to the doors and to receive the side thrust, thus preventing the doors from leaving the 40 rails.

The invention further provides a ledge 11 which in conjunction with a ledge which may be provided on the side of the compartment opposite to the doors serves to support 45 trays 12. For the purpose of effectively covering the edge 3 of the wall 4 of the wooden structure, the strip 2 may include flanges 13 and 14. The flange 14 is positioned to overlap the edge of a metallic lining 15 covering the inner side of the wall 4 and permitting any condensate which may accumulate upon the ledge to flow into the compartment of the show case and drain off through the outlet pipe as commonly provided.

50 The present invention may of course be applied to many types of display cases where sliding doors are employed, and it has been found to be of great advantage in connection with display cases for exhibiting perishable articles such as meats, fish, and produce of various kinds.

55 The formation of a metallic cover plate in combination with tracks, stop and tray-support reduces the number of separate parts

heretofore required and at the same time improves the appearance and sanitary condition of a display case. The importance of the invention from a hygienic standpoint alone can readily be appreciated and when combined with its mechanical features makes the invention a valuable advance in the art.

It is to be appreciated that the strip 2 may be manufactured by a tool and die or rolling operation and that any desirable lengths may be supplied, it merely being necessary for the manufacturer of display cases to cut the strips to the desired lengths to adapt them to cases of any special type 75 or length. Furthermore, it is obvious that the older types of cases may be remodeled to the extent of having the strips substituted for their present construction.

80 Although a preferred embodiment of my invention has been illustrated and described, it is obvious that those skilled in the art may modify the same, however, such modifications as come within the terms of the appended claims are contemplated as falling 85 within the scope of my invention.

What I claim is:

1. A combined cover plate and track for display cases, comprising an elongated strip of metal having a flat body portion, two 95 downwardly extending flanges engaging the sides of said body portion and integral therewith, two longitudinal corrugations pressed outwardly from said flat body portion in a direction opposite to said flanges, and another longitudinal corrugation extending outwardly from adjacent the edge of said flat body portion in the same direction as said first mentioned corrugations, 100 said first-mentioned corrugations adapted to serve as tracks and said last-mentioned corrugation adapted to serve as a stop.

2. A combined cover plate and track for display cases, comprising an elongated strip of metal having a flat body portion, two 110 downwardly extending flanges engaging the side of said body portion and integral therewith, two longitudinal corrugations pressed outwardly from said flat body portion in a direction opposite to said flanges, another longitudinal corrugation extending outwardly from adjacent the edge of said flat body portion in the same direction as said first mentioned corrugations, 115 and a ledge extending outwardly from said last-mentioned corrugation for supporting a tray.

3. A combined cover plate and track for display cases and the like, comprising a flat strip of metal having a plurality of corrugations pressed outwardly therefrom to form tracks upon which doors may slide, another corrugation pressed outwardly from said strip of metal and disposed adjacent the inner edge thereof to serve as a stop to prevent displacement of said doors, said strip also 120

being provided with means adjacent its inner edge to form a shelf for trays and the like.

4. A combined cover plate and track for display cases and the like, comprising a flat strip of metal having angular flanges along its longitudinal edges to furnish means for securing the cover plate to an object, and a plurality of longitudinal corrugations

pressed outwardly from said strip of metal 10 in a direction opposite to said flanges, and a shelf intermediate one of said corrugations and one of said flanges and adapted to serve as a support for a tray.

In testimony whereof, I have hereunto 15 subscribed my name this 2 day of April, 1925.

CHARLES E. WICKE.
